FRANK G. DELBON

BY

Cliff G. Lee
ATTORNEY

UNITED STATES PATENT OFFICE.

FRANK G. DELBON, OF BROOKLYN, NEW YORK.

SHOE LAST.

Application filed October 19, 1921. Serial No. 508,650.

To all whom it may concern:

Be it known that I, FRANK G. DELBON, a citizen of the United States, and a resident of Brooklyn, in the county of Kings and 5 State of New York, have invented certain new and useful Improvements in Shoe Lasts, of which the following is a specification.

The invention consists in the production of a novel last for use in the manufacture 10 of shoes adapted to the feet of men, women and children.

The last of my invention is built on lines and in accordance with a system of measurements which have not heretofore been followed in the manufacture of lasts, and this 15 same system may be properly followed in the grading of the sizes of lasts or the development of a set of lasts from, say, a "4B" model.

20 One object of the invention is to provide for the manufacture of shoes (from a small size for children to a large size for adults) suited to the geometrical and anatomical construction of a normal human foot and 25 adapted to preserve, or regain where lost, the original lines of the foot, the shoes also being of good appearance and faultless fit.

My invention therefore provides a shoe 30 last which is novel in its form and relative proportions and produced by a system adapted to be followed in the production of a set of lasts or lasts of graded sizes.

In carrying out my invention I have had 35 particular regard to the proper maintenance in a normal working condition of the various bones, joints and ligaments of the human foot, to preserve the normal condition of the plantar arch and to restore such arch, if weakened, to a normal working condition, 40 and to provide for the foot what I may term an effectual three-part-support, as will be explained hereinafter.

The admeasurements and system by which 45 I produce my novel last may be better understood on reference to the drawings illustrative of the same. I may say generally however that the last both longitudinally and transversely considered is subdivided into three parts or divisions, one-third in length 50 extending from the toe to the ball and two-thirds extending from the heel to the ball, while the division line for the instep is one-half of the length of the last.

The invention will be fully understood 55 from the detailed description hereinafter

presented, reference being had to the accompanying drawings, in which:

Fig. 1 is a side elevation, diagrammatically shown, of a last embodying the features of my invention, Fig. 1 showing a diagram of 60 the lines on which the admeasurements or relative proportions of the last are patterned;

Fig. 2 is a side elevation of the finished last; 65

Fig. 3 is a top view of the same;

Fig. 4 is a bottom view of the same;

Fig. 5 is a vertical transverse section 70 through the same, taken on the dotted line 5-5 of Fig. 2;

Fig. 6 is a further side elevation of the last illustrating the method followed for patterning the last in accordance with the varying heights of the heels to be employed on the shoes made therefrom; 75

Fig. 7 is a diagram of a human foot with scale lines indicated thereon denoting a portion of my method for obtaining the outlines for the last, and

Fig. 8 is a plan view defining a further 80 portion of my method for obtaining the correct outlines for the last.

In constructing my last I make it longer than the human foot so as to allow space in the shoes for the freedom of the toes, and 85 this extension of the last is represented by the line X in Figs. 1, 6, 7 and 8. This extension X is usual in the construction of lasts and is additional to and forms no part of my system in attaining the proper admeasurements for the main portion of the last. 90

In arriving at the proper proportions for the pattern or model last, I start within the confines of an angle represented by a 95 horizontal line A and a vertical line B, and, referring to Fig. 1, determine the height of the heel for the shoe to be built, this height, as an illustration, being represented by the line C. The length of the last, disregarding the extension X, is evenly divided longitudinally into thirds, as indicated by the lines D, E, F, one-third of the length 100 extending from the toe to the sesamoid bones or the anterior ends of the metatarsal bones, denoted at the line G, and the other two-thirds of the length extending from the said line G to the back heel-line H. I also 105 subdivide the length for the last by a central vertical line I, which divides the last 110

- into two equal parts and is an instep defining line for a human foot standing on a flat horizontal surface. The line I changes position in accordance with the height of 5 the heel line C, since when consideration is paid to the height of the heel the rear end of the last becomes more or less elevated above the base line A, and, in the diagram shown in Fig. 1, I indicate the instep line 10 I, due to the elevation of the heel part of the last, as having been deflected forwardly to the position of and forming line J. In my pattern and system a straight upwardly and rearwardly inclined line K extends 15 from the anterior end of the metatarsal bones, denoted at line G, to the lower rear edge of the heel portion 10 of the last, and this line K always being followed regardless of the height of the heel line C, the 20 instep-line J must intersect with it and the vertical line I, at the point L, the line J being at right angles to the line K. A ball admeasurement line M is drawn at right angles to the forward end of the 25 line K, and this line M in the primary admeasurement of the human foot standing flat starts at the line N which is at right angles at the base line A and denotes one-third of the length of the foot. The tilting 30 of the rear end of the last upwardly in accordance with the heel admeasurement throws the line N forwardly to the position of the ball line M. The waist line for the last is determined by the line O 35 which extends from the upper end of the ball line M to the intersection point L or lower end of the instep line J. The waist measurement for the last is around the last on the line O, and I call attention to the 40 fact that in accordance with my invention this waist measure line extends downwardly and rearwardly and considered from the inner side of the foot extends from a point above the anterior end of the 45 large metatarsal to a point below the rear end of said bone, as may be understood on reference to Fig. 7, said line extending around the foot and not crossing on said anterior end of said bone. Both lines J, M stand at right angles to the line K and are 50 parallel with each other. The point L is a fixed point, and the intersecting point of lines M and O will follow the thickness of the foot and accordingly with the thickness 55 of the last and the consequent necessary height of the line M, but wherever such intersecting point may be located the waist measure will be around the foot on said point and the point L or on the line O. 60 Since the intersecting point of lines M and O becomes higher or lower in accordance with the thickness desired for the last, the angle between the lines O and K will vary accordingly. There can be no fixed angle 65 between lines O and K except for one known thickness of last and one known heel height. The intersecting point of the lines M, O, is always definite, since with any desired thickness of last, said point is on the line M at the top of the last, whether the 70 last is two inches thick at said line or of greater or less thickness, and the waist line O will extend from said point on line M determined by the thickness of the last, to the aforesaid point L. 75
- The upper instep point for the last from which the shoe curves upwardly to the front portion of the leg, is denoted at P; and this point, according to my system, in every vertical thickness of the last required, 80 will always be on the line Q, which starting from the juncture of the angle-lines A, B, inclines upwardly and forwardly and stands on an angle of 45 degrees to both lines A, B. The admeasurement for the back part 85 of the last is found by the line R which inclines rearwardly from the point P to the lower rear point of the heel portion 10 of the last at the vertical line B. The angle of the line R necessarily varies in accordance 90 with the location of the point P on the line Q, this location varying with the heel-height and the initial thickness of the last at the instep thereof, but said line R whatever its angle may be is definitely located 95 and will correctly give the back measure for the last. Lasts must vary in thickness in accordance with the feet for which the shoes are to be made, and with my invention the high instep point of the last, denoted at 100 P, when positioned on the right angle line Q, with the back of the heel of the last against the vertical line B, enables me to obtain a correct back admeasurement on the line R for all lasts regardless of their thickness, since with each thickness of last the point P thereof is a definite point for that thickness and when positioned on the line Q with the back of the heel portion against the line B, the admeasurement on the line R 105 for that thickness is correct. 110
- An essential consideration in the manufacture of lasts consists in giving the proper curvature to the inner side thereof between the ball and the heel. The extent and character of this curvature is important especially when the plantar arch of the foot is to be properly supported. In accordance with my system I find it entirely convenient to lay out the curvature for the inner 115 side of the arch of the last by the diagram represented in Fig. 1, in which I show a line S drawn parallel with the base line K and starting from the intersection point at the upper ends of the ball line M and waist 120 line O, this line S extending upwardly and rearwardly parallel with the line K and at right angles to the ball-line M. A vertical line T denotes the rear one-third division of 125 the length of the foot, and this line T, as 130

the heel portion of the last is raised or lowered in accordance with the heel height line C, becomes deflected with relation to the last, and when the last is for a heel of the 5 height of the line C, the upper portion of the line T breaks at the base line K and becomes deflected forwardly and then constitutes the line U, the position of this line U varying with the height desired for the 10 heel of the shoe. In the present instance the break of the line T is denoted at the line K, and the line U standing at right angles to the line K and extending to the line S denotes the central point V for the 15 curvature to be formed at the inner arch side of the last. The upper line for the curvature at the inner side of the last extends on the arc of a circle from the juncture or ball point of the lines K, M, through the 20 point V and to the rear end of the line K at the heel portion of the last, and said arc line is denoted by the letter W. The curvature of the last, at the sole portion thereof and at the base of the aforesaid arch curvature, is defined by the arc lines Z, Y, the 25 line Z extending downwardly and forwardly on a convex arc from the point V to the intersection point of the lines K, M, and the line Y extending downwardly and rearwardly on a concave arc from the point V to the front of the heel rest. The arc-line Z is struck from a point representing the apex of an equilateral triangle whose base would be represented by a straight line drawn 30 from the point V to the aforesaid intersection point of the lines K, M. The arc-line Y is struck from a point representing the apex of an equilateral triangle whose base would be represented by a straight line drawn 35 from the point V to the point on the heel line B at which the line R of Fig. 1 would if continued toward the right cross said line B.

In Fig. 6 I present a diagram illustrating 40 the changes in the various lines hereinbefore referred to which take place with variations in the height of the heel desired for the shoe to be made from the last, and therein I denote the several heel height lines by a, b, 45 c, respectively. When the heel height is that represented by the line a, the base line K at Fig. 1 will become situated at line K'; when the heel height is represented by the line b the line K of Fig. 1 becomes positioned at line K'', and when the heel height is represented by the line c the line K of Fig. 1 becomes positioned at line K''. With the varying heel heights the foot center line I remains in its central position and the 50 instep line J of Fig. 1 becomes positioned at J', J'' and J''', respectively, while the ball line M of the natural foot, when standing flat, becomes positioned at the lines M', M'' and M''' of Fig. 6. In regard to the various 55 heights of heels for the shoes I may say that

the line Q of Fig. 1 remains in its original position, as I show in Fig. 6, while the line R varies in inclination as R', R'' and R''' of Fig. 6. It seemed unnecessary to show additional diagram lines in Fig. 6, having indicated the main lines therein with the changes following the different heights for the heels.

In Fig. 7 I represent on a diagrammatic representation of the human foot, the instep line J, ball line M, base line K, 45° angle line Q, and the admeasurement line R corresponding with the same lines presented in Fig. 1.

In Fig. 8, which represents the sole portion of the last and gives an outline for the insole pattern, it will be seen that the bottom of the last is divided into thirds and halves in length, the same as the admeasurements shown in Fig. 1, and that longitudinally the last is divided into thirds to harmonize with foot admeasurements and serve as a guide for the formation of the last, the division lines for the thirds being lettered d and the line for the halves being e indicated at e. The diagram in Fig. 8 is outlined by an oblong, and a diagonal line f extends from the lower corner of the oblong at one end of the outline to the opposite upper corner portion of the oblong at the upper end of the extension line X. The oblong shown in Fig. 8, aside from the extension at X, has a width equal to one third of its length. The line g is the transverse ball line, and it stands at right angles to the line f and extends from the point G rearwardly to the opposite side of the foot or the sole of the last, finding its true position by starting at G and extending at right angles across the line f. I also apply on the diagram shown in Fig. 8 a guiding or direction line h which also is at right angles to the line f and starts at the one-third division point i and extends on a rearward incline across to the opposite side of the foot and finding its position from the fact that it starts at the point i and crosses the aforesaid line f at right angles thereto. The upper end of the line h (looking at Fig. 8) extends toward the heel one-third of the distance between the line d and the heel end of the last or of the oblong represented in Fig. 8. The metatarsal arch is defined between the lines g, h, the curvature at the inner side of the last and shoe being forwardly of the curvature of the last for the outer side of the shoe, as represented by the diagonal disposition of the lines g, h.

The line g denotes the ball line for the sole of the last and consequently for the shoe, and the line h defines the forward edge of the heel-seat and which on the last is usually represented by a metal plate as shown in Figs. 2 and 4.

The curved lines Z, Y denote approxi-

5 mately the curvatures carried down under the sole of the last, the line Z extending from the point V of Fig. 1 downwardly and forwardly under the shank and vanishing under the ball of the sole, as indicated in Fig. 4, and the line Y, starting at the point V, curving downwardly and rearwardly under the shank to the point of the line h where the same meets the forward corner of 10 the heel-rest at the inner side of the last. Between the lines Z, Y is formed the deeper concavity of the recess at the inner side of the shank of the last. In Fig. 4 I have indicated the line U to illustrate its direction 15 and terminus under the shank of the last, said concavity along and adjacent to said line affording an effective support for the transverse arch of the foot and stopping at a line about two-thirds across the bottom of 20 the last toward the outer side thereof where at in a foot is located the fifth metatarsal.

25 The last constructed in accordance with the method or system hereinbefore described is illustrated in Figs. 1 to 5 inclusive, in which 15 designates the last as a whole, and 10 the heel portion, 16 the shank, 17 the forward sole and 18 the instep portions thereof. The heel portion 10 usually has secured on its lower side a metal heel plate 19, and 30 in the illustration I have shown the last as made in two parts 20, 21, but the last may be formed in one piece of material if desired. The forward sole portion 17 of the last is about one-third of the length of the 35 shoe to be produced, plus an extension for the toe, represented by the line X in Fig. 1. The last made in accordance with my system has a more elevated instep 18 than is usual in lasts and a smaller waist portion 40 measured on the line O than lasts as heretofore constructed, and these proportions as to the instep and waist result in a better fitting shoe.

45 The instep portion 18 of the last is of special formation, as shown in Figs. 3 and 5, being of sharp triangular or cross-section and having its apex or sharp ridge 22 extending downwardly and forwardly in an approximately straight line toward that 50 portion of the last representing the large toe of the foot, said ridge 22 being, as shown in Fig. 3, slantingly directed toward the inner side of the forward end of the last and at its forward portion being on a concave 55 curve and merging into the upper forward portion of the last at about the upper end of the ball line M. In its upper portion the ridge or apex line 22 is on a convex curve, and hence said line as a whole represents a 60 compound curve. The triangular formation of the instep portion 18 becomes less acute toward the forward portion of the last and finally disappears in the general upper surface of the forward portion of the last. The 65 high point for the instep portion of the last

is denoted at P, this being the point at which the material of a shoe made on the last would turn upwardly to form the ankle portion of the shoe. The location of the intersection point P on the line Q will vary with 70 the height of the heel to be worn. The point P becomes more or less elevated according to the heel-height, as represented in Fig. 6, said point P being on the line Q where said line crosses upwardly from the upper edge 75 or thickness-line of the last. The line R drawn from the lower back point of the heel across the line Q at the point P creates an intersection point, which represents the high point for the instep and from which 80 on the line R the measurement for the back portion of the last is given, the line R passing around the last on the angle shown representing such measurement, and the intersecting point P positioning the line R for 85 correct measurement.

At the inner side of the ridge or apex line 22, the last extends downwardly therefrom on a convex curve 23 to the upper outer edges of a recess 24 which I form at 90 the inner side of the shank portion of the last and which is of material importance and considerable dimensions, said recess being generally defined by the arched line W in Fig. 1 and having a curved convex surface formation and being longitudinally concaved and extending down under the shank of the last and terminating at its forward edge slightly in rear of the ball line g of Fig. 8; as shown in Fig. 4, and at its 100 rearward portion ending at the apex of a longitudinal triangular ridge or rib 25 which is positioned adjacent to the outer side of the last and sets in from the outer side edge of the shank a distance about one-third of 105 the width of the shank. The outer side of the shank is curved inwardly under the shank on a convex surface formation to the longitudinal ridge or rib 25, thereby forming an outer side recess 26 and aiding in the 110 formation of said ridge 25. At its forward end the ridge 25 terminates in a triangular formation 27 (Fig. 4) upon which and directly to the front of the ridge 25 is a downwardly projecting convex elevation 28, this 115 being located in position to form a shallow seat in the sole of a shoe for the anterior end of the outer side metatarsal bone of the foot. The ridge or rib 25 results in the formation in the shoe made from the last, of a 120 longitudinal seat or rest for the outer side bones of the foot which are low at this location and are with the use of my invention permitted to take a natural comfortable position and not compelled to withstand pressures except those intended by nature for them; this feature of my last I regard as 125 important and entirely novel.

At its forward edge the recess 24 curves inwardly and rearwardly below the shank, 130

as denoted at the line 29 in Fig. 4, and just forward of said line 29 the ball of the last is formed with a downwardly extending convex projection 30, whose presence on the 5 last results in the formation in a shoe made therefrom of a concave seat for the sesamoid bone on or the anterior end of the inner side metatarsal bone of the foot.

Between the projections 28, 30 on the sole 10 portion of the last, the last is slightly concaved, as at 31, to meet the natural requirements of the forward end of the plantar arch of the foot.

The bottom portion of my last provides 15 a shoe sole adapted to enable a foot to have the strains thereon properly distributed and thereby to prevent such strains from weakening or otherwise injuring the ligaments of the foot. The major portion of the 20 weight of the human body on a foot should be received by the inner side of the foot, and this I provide for by the extent of the recess 24 which provides, in the shoe, a full bearing support for the fleshy part of the 25 foot under the arch and for the bones of the arch. The bottom portion of my last provides, in the shoe, what I regard as a three-part support for the foot, one being at the heel, which gives support to the main arch 30 from the high instep to the ankle and to the main leg structure; another being at the walls of the recess 24 from the heel to the projection 30, and the third being from the heel along the ridge 25 to the projection 28. 35 The anterior portion of the metatarsal arch or ball of the foot is not only supported by the seats afforded by the projections 28, 30, but also by the material between said seats, and undue strain thereon is prevented by 40 the supports afforded by the ridge 25 and walls of the recesses 24, 26.

My last has been designed with the view 45 of so distributing the strains on a foot as to avoid weakening of or other injury to the ligaments about the tarsal and metatarsal bones, to properly support the plantar arch and to provide efficient bearing surfaces for the sole portion of a foot, having regard not only to the support afforded by 50 the sole of a shoe generally but to a support which will ensure comfort to the wearer of the shoe and save the foot against the effects of an unnatural distribution of strains thereon.

55 The last shown and produced by the system I have hereinbefore outlined, is adapted to the production of shoes suited to the geometrical and anatomical construction of the human foot, to preserve the arch construction of the foot and to relieve the foot from the effects of weakened arches.

I have hereinbefore indicated certain 60 relative proportions for certain parts of the last and these admeasurements should be followed when the best results are to be at-

tained. I do not limit my invention, however, to the exact proportions stated, since to do so would leave my invention open to appropriation by others on slight modification of the admeasurements indicated. I 70 regard my last as distinctly novel and as constituting an important advance in the art and hence desire to receive adequate protection for my invention.

What I claim as my invention and desire 75 to secure by Letters-Patent, is:

1. A shoe-last of the character described having at its inner side a concave arched recess spreading downwardly and longitudinally below the shank of the last and extending from the ball line to the heel, said arched recess also extending transversely across the shank on curved lines for a distance approximately two-thirds of the width of the shank, whereby a substantial arch is 80 provided to create in a shoe an arch support for the first, second, third and fourth metatarsals and inner portion of the plantar fascia, and said last having at its outer side a comparatively shallow arched recess 85 having convex surfaces and extending transversely across the shank a distance approximately one-third of the width of the shank, and said shank having at the line between said inner and outer side arches a longitudinal ridge to form in the shoe a rest and support for the fifth metatarsal and outer portions of the plantar fascia. 90

2. A shoe-last as claimed in claim 1, in which the forward portion of the inner side 100 arched recess extends inwardly and rearwardly on a rearwardly curved line at the rear end of the inner side portion of the sole, and in which the forward portion of the outer side arched recess extends inwardly and rearwardly at the rear end of the outer side portion of the sole, and in which the inner side recess extends forwardly on concave lines into the middle portion of the rear end of the sole to adapt the 105 shoe for the requirements of the forward end of the plantar arch of the foot and leave at opposite sides of said concave portion seats for the anterior ends of the first and fifth metatarsals. 110

3. A shoe-last of the character described having a forward portion about one-third of the length of the last and a waist portion determined between two upwardly and forwardly inclined parallel lines one of 115 which denotes the mesne instep portion of the last, said lines standing at right angles to an inclined base line running from the ball of the last to the outer end of the heel-seat, and the forward one of said parallel lines at its lower end starting from the forward end of said inclined line, and the other of said parallel lines intersecting said inclined line at a point denoting one-half of 120 the length of the last, the admeasurement of 125 130

said waist portion being on an inclined line extending from the point on said forward line denoting the thickness of the last at that portion to the intersecting point of the rear one of said parallel lines with said base line.

4. A shoe-last of the character described having a forward portion which is about one-third of the length of the last, a waist portion and an upper instep portion, said waist portion being determined between two upwardly and forwardly inclined parallel lines, the rear one of which denotes the mesne instep portion of the last, said lines standing at right angles to an inclined base line running from the ball of the last to the outer end of the heel-seat, and the forward one of said parallel lines at its lower end starting from the forward end of said inclined line, and the other of said parallel lines intersecting said inclined line at a point denoting one-half of the length of the last, the admeasurement of said waist portion being on an inclined line extending from the point on said forward line denoting the thickness of the last at that portion to the intersecting point of the rear one of said parallel lines with said base line, and the admeasurement for the back portion of the last being on an inclined line extending from the high instep point of the last to the rear end of the heel seat for the last when said instep point is on a line extended through the last from the vertex of and bisecting a right angle confining the last at its sole and back portions.

5. A shoe-last of the character described having a sharply defined instep portion of

triangular cross section, and the admeasurement for the back portion of the last being on an inclined line extending from the high instep point of the last to the rear end of the heel seat for the last when said point is on a line extended through the last from the vertex of and bisecting a right angle confining the last at its sole and back portions.

6. A shoe-last of the character described having a forward portion which is about one-third of the length of the last, the ball-portion of the last being at the rear end of this one-third division, an inner side concave arched recess spreading downwardly and longitudinally below the shank of the last and terminating at its front portion adjacent to the ball of the last and at its rear portion at the side of the heel-seat, said recess being confined between an inclined base line extending from the base of said one-third division of the last to the lower rear edge of the heel-seat and an upper inclined line parallel with said base line and extending through the heel portion of the last from a point denoted at the upper end of a line extending upwardly and forwardly from and at a right angle to the forward end of said base line and ending at the top of the last, and the deeper middle portion of the recess being denoted by a line connecting said inclined parallel lines and starting from the middle point of said base line and standing at a right angle thereto.

Signed at New York city, in the county of New York and State of New York, this 17th day of October, A. D. 1921.

FRANK G. DELBON.
